CLAIM

The ornamental design for an surgical clip applier, as shown and described.

DESCRIPTION

FIG. 1 is a perspective view of surgical clip applier showing my new design;

FIG. 2 is a top view thereof;

FIG. 3 is a first side view thereof, the opposite side being a mirror image;

FIG. 4 is a bottom view thereof;

FIG. 5 is a proximal view thereof; and,

FIG. 6 is a distal view thereof.

The broken lines are intended for the purposes of environmental structure only and form no part of the claimed design.
